(Continued)

Primary Examiner — Rhea Shields(74) *Attorney, Agent, or Firm* — Birch, Stewart, Kolasch & Birch, LLP(57) **CLAIM**

The ornamental design for a socket for vacuum tube, as shown and described.

DESCRIPTION

1. Socket for vacuum tube

1.1 : Perspective

1.2 : Front

1.3 : Back

1.4 : Left

1.5 : Right

1.6 : Top

1.7 : Bottom

1.8 is a perspective view of the socket for vacuum tube shown in an environment.

In Reproduction 1.8 the broken lines are for the purpose of illustrating environment only and form no part of the claimed design.

1 Claim, 8 Drawing Sheets(56)
